UNITED STATES PATENT OFFICE

GEORGE DAVIS HALL, OF KEARNEY, NEBRASKA

AUTOMATIC DOOR

Application filed June 19, 1929, Serial No. 372,126.

This invention appertains to a novel door opening and closing device and has for one of its primary objects the provision of means actuated by a person's weight on a platform on either side of the door for sliding the door to a fully open position, the door being automatically returned to its closed position when the weight of the person is removed from the platform.

Another important object of my invention is the provision of a door slidably supported by a suitable track with a novel hinge operatively connected to the door and door frame, with an electric motor actuated mechanism for spreading the leaves of the hinge for moving the door to its closed position, the circuit through the motor being controlled by a platform operated switch, the hinge being automatically returned to its closed position for sliding the door to its normal position by spring means when the circuit through the motor is opened.

A further salient object of the invention is the provision of novel means for constructing the hinge and for connecting the hinge to the door and door frame, whereby the door can be slid to an open and closed position in an arcuate path, thereby eliminating the necessity of sliding the door in a straight line and permitting the use of sliding doors in vestibules and other confined places.

A further object of my invention is the provision of novel means for breaking the circuit through the operating motor for the hinge when the door reaches its fully opened position irrespective of whether the person is on the platform or not, thereby preventing injury to the motor and the operating parts of the device.

A still further object of my invention is to provide an improved door opening and closing mechanism of the above character, which will be durable and efficient in use, one that will be simple and easy to manufacture, and one which can be placed upon the market and incorporated with a door at a reasonable cost.

With these and other objects in view, the invention consists in the novel construction,

arrangement and formation of parts, as will be hereinafter more specifically described, claimed, and illustrated in the accompanying drawings, in which drawings:

Figure 1 is a front elevation of a door showing my improved appliance connected therewith, the control platform being shown in section;

Figure 2 is a vertical section through the door and door frame taken on the line 2--2 of Figure 1 looking in the direction of the arrows showing the operating mechanism in side elevation;

Figure 3 is a top plan view of the improved device, the wall being shown in horizontal section, the track for the door being shown broken away and in section;

Figure 4 is a longitudinal section through the platform illustrating the circuit closer for the motor incorporated therewith;

Figure 5 is a perspective view of the operating mechanism showing the device in its operated position for moving the door to its fully open position;

Figure 6 is a vertical section showing a slightly modified form of control platform.

Referring to the drawings in detail, wherein similar reference characters designate corresponding parts throughout the several views, the letter A generally indicates a building provided with angular related walls 10 and 11, the wall 10 being provided with the door opening; B the door for the opening, and C my improved mechanism for opening and closing the door.

The door B can be of any preferred character and is of the sliding type and is carried by a suitable supporting track 12 carried by the walls 10 and 11 above the door opening. The rear corner of the door is provided with a wheeled bracket 13 mounted in the track, while the opposite corner of the door is supported by part of the operating mechanism as will be later described. The part of the door which is supported by a part of the operating mechanism is provided with a guide roller 14 which also engages the track 12.

My operating mechanism C comprises a hinge-like structure 20 including inner and

outer leaves 21 and 22 which have their forward or inner ends connected by a king bolt 23. The leaf 21 includes upper and lower straps 24 which are held in spaced relation by brace bars or straps 25. The outer ends of the straps 24 are angled as at 26 and are pivotally secured by means of a pivot pin or bolt 27 to a supporting bracket 28 which is bolted or otherwise secured to the door frame or wall directly above the door opening and adjacent to the rear edge of the door B. The outer ends of the upper and lower straps 29 which constitute a part of the leaf 22 are pivotally connected by means of a pin or elongated bolt 30 to a supporting bracket 31. The lower end of the bracket 31 is offset inwardly and extends below the door opening and is rigidly connected, by means of bolts or the like, to the door B as at 32 adjacent to the inner end thereof and this bracket in effect supports the inner edge of the door. The straps 29 of the link 22 are held in a spaced relation and are braced by means of straps or brace bars 33. In order to further aid in supporting the door, the lower straps 29 have bolted or otherwise secured thereto a depending arm 34 which is likewise rockably mounted on the lower end of the pivot bolt 30 and rests upon a pivot ear 35 forming a part of the bracket 31. The straps 29 adjacent to the point of connection thereof with the pivot bolt 23 are angled inwardly as at 36, as can be clearly seen from the drawings.

35 The upper straps 24 of the link 21 have bolted or otherwise secured thereto an electric motor 37 of the desired horsepower and the motor has keyed to its armature shaft a beveled pinion 38 which meshes at all times 40 with a relatively large beveled pinion 39 rotatably mounted upon a stub shaft 40 secured to the upper strap 24 of the link 21. This beveled gear 39 has eccentrically secured thereto a pitman rod 41 which is in 45 turn rockably connected as at 42 to the upper strap 29 of the link 22, for a purpose which will be now described.

50 Presuming the door B is closed, as shown in full lines in Figure 3 of the drawings, the pitman rod 41 will have its inner end adjacent to the motor 37 and the links 21 and 22 will be in their collapsed position, as shown. When the circuit through the motor 37 is closed, the gear 39 will be rotated causing 55 an outward thrust on the pitman rod 41 which will in turn push out on the link or hinge leaf 22 thus moving the door to its open position and carrying the door around the curved track 12. As soon as the circuit 60 is broken through the motor 37 the leaves 21 and 22 will be automatically returned to their collapsed position and the door to its closed position by means of a relatively heavy coil spring 43 which is placed about 65 the king bolt 23 with its opposite ends en-

gaging the leaves 21 and 22. This spring is normally under tension and as the leaves are moved to their spread position the spring is further tensioned so that when the circuit is opened through the motor the 70 spring will immediately function to return the leaves to their normal position. In order to further aid in the swinging of the leaves to their normal position, the pivot bolt 27 has coiled about the same a relatively heavy 75 coil spring 44 which has its opposite ends engaging respectively the link 21 and the supporting bracket 28.

I have provided novel means for closing the circuit through the motor 37 and this 80 means comprises platforms or approaches 50 and 51 arranged on opposite sides of the door opening and I so arrange these platforms that the same will be depressed when a person stands upon the same. Each one of the platforms may be made of sheet metal 85 and arranged within a suitable pressed metal casing 52. In buildings under construction, this sheet metal casing 52 can be countersunk within the floor 53 of the building D and in buildings already built the platforms 52 can be secured to the upper face of the floor and in this instance I prefer to incline the outer faces of the casing as at 54 to facilitate the passage of persons or 90 trucks over the platforms or approaches. As shown, the inner edge of the platform 50 is offset as at 55 and supports the inner edge of the platform 51. The opposite edges of the platforms 50 and 51 can rest upon supporting strips 56 and the inner edges of the platforms are normally held in a raised position by relatively heavy leaf springs 57 which will flex under weight. An angle iron strip 58 is employed for limiting the 100 downward swinging movement of the inner edges of the platforms 50 and 51 as shown. A resilient contact strip 59 is carried by the casing 52 and is adapted to be engaged by a contact strip 60, which is insulated from the platform 51, when the platforms are 105 depressed. In accordance with this invention feed and return wires 62 and 63 are provided which are connected with a suitable source of electric energy and the wire 110 63 has interposed therein the electric motor 37 and this wire 63 is connected to the resilient contact 59. The wire 62 is electrically connected with the contact strip 60 and thus when the platforms are depressed under 115 weight the circuit will be closed through the motor consequently bringing about the opening of the door, as heretofore described.

I prefer to provide means for breaking 120 the circuit through the motor 37 when the door reaches its fully open position and thus I interpose a switch 65 in the length of the wire 62 and the switch may include resilient 125 normally engaged contacts 66. The door B 130

can carry a rigid trip 67 for engaging one of the contacts when the door is in its fully open position for moving the same out of engagement with the other contact and thus 5 when the door reaches its fully open position the switch will be opened and the circuit consequently interrupted through the motor.

From the foregoing description it can be 10 seen that I have provided a novel means for automatically opening and closing a door in a highly efficient and durable manner without the necessity of the user employing his hands for any operation incident to the 15 opening and closing of the door at all.

Changes in details may be made without departing from the spirit or the scope of this invention, but:

What I claim as new is:

- 20 1. The combination with a wall having a door opening and a sliding door for said opening, of means for opening said door comprising a hinge member including laterally extending leaves pivotally connected together and to the door and wall respectively, a wheel rotatably mounted on one leaf, a pitman eccentrically connected to the wheel and pivotally connected to the other leaf, and means for actuating the wheel.
- 30 2. The combination with a wall having a door opening and a sliding door for said opening, of a door opening and closing mechanism comprising a hinge member including laterally extending leaves pivotally connected together and to the door and wall respectively, spring means normally holding the leaves in a collapsed position and the door in its closed position, and means for opening the door against the tension of 40 said spring means including a wheel rotatably mounted on one leaf, a pitman eccentrically connected to the wheel and pivotally connected to the other leaf, and means for actuating the wheel.
- 45 3. The combination with a wall having a door opening and a sliding door for said opening, of a door opening and closing mechanism comprising a hinge member including a pair of leaves hingedly connected together and pivotally connected to the door and wall respectively, a gear rotatably mounted on one leaf, a pitman rod eccentrically connected to the gear and pivotally connected to the other leaf, an electric motor 50 for operating the gear, and spring means normally holding the leaves in a collapsed position and the door in a closed position.
- 55 4. The combination with a wall having a door opening and a sliding door for said opening, of a door opening and closing mechanism comprising a hinge member including laterally extending leaves pivotally connected together and to the door and wall respectively, spring means normally holding the leaves in their collapsed position and the

door in its closed position, means for opening the door against the tension of said spring means including an electric motor secured to one leaf, a beveled gear rotatably mounted on the same leaf, a pinion keyed to the armature shaft of the motor and meshing with said beveled gear, and a pitman eccentrically connected to the beveled gear and pivotally connected to the other leaf. 70

5. The combination with a wall having a door opening and a sliding door for said opening, of a door opening and closing mechanism comprising a hinge member including leaves hingedly connected together and to the door and wall respectively and projecting normally laterally therefrom, spring means normally tending to collapse the leaves and hold the door in a closed position, means for opening the door and spreading said leaves including a wheel rotatably carried by one leaf, a pitman eccentrically connected to the wheel and pivotally connected to the other leaf, an electric motor carried by the first leaf and operatively connected to said wheel, and means for closing the circuit through the motor including platform operated switches arranged on opposite sides of the door opening. 80

6. The combination with a wall having a door opening and a sliding door for said opening, of a door opening and closing mechanism comprising a hinge member including leaves hingedly connected together and to the door and wall respectively and projecting normally laterally therefrom, spring means normally tending to collapse the leaves and hold the door in a closed position, means for opening the door and spreading said leaves including a wheel rotatably carried by one leaf, a pitman eccentrically connected to the wheel and pivotally connected to the other leaf, an electric motor carried by the first leaf and operatively connected to said wheel, means for closing the circuit through the motor including platform operated switches arranged on opposite sides of the door opening, and means for breaking the circuit through the motor when the door has reached its fully open position including a switch in the motor circuit and means for opening the switch including a trip carried by said door. 100

7. In a sliding door opening and closing mechanism, a hinge member including a pair of leaves hingedly connected together and to the door and door frame, means normally holding the leaves in a collapsed position and means for spreading said leaves including a pitman rod hingedly connected to one leaf and means carried by the other leaf for actuating the pitman. 120

8. The combination with a wall having a door opening and a sliding door for said opening, of a door opening and closing mechanism including a bracket rigidly connected 130

to the wall above the door opening and in advance of the door when in its normally closed position, a bracket secured to the door adjacent to the rear edge thereof, a hinge member including a pair of leaves, one of said leaves being hingedly connected to the bracket on the door, the other leaf having its inner end angled and extending over the first leaf and hingedly connected to the bracket carried by said wall, means hingedly connecting the leaves together, spring means normally holding the leaves in a collapsed position and the door in its closed position, and means for spreading said leaves including a beveled gear rotatably carried by the leaf hingedly connected to the wall bracket, a pitman eccentrically connected to the beveled gear and pivotally connected to the other leaf, an electric motor, and a pinion connected to the armature shaft of the motor and meshing with the beveled gear.

9. The combination with a wall having a door opening and a track above the door opening, of a sliding door for the opening having a wheeled bracket carried by the inner end of the door and slidably mounted in the track and a roller guide carried by the rear edge of the door engaging the track, of a door opening and closing mechanism supporting the rear edge of the door including a hinge member having a pair of leaves pivotally connected together and to the rear edge of the door and the wall respectively, spring means normally tending to collapse the said leaves, and means for spreading said leaves including a wheel rotatably mounted on one leaf, a pitman rod eccentrically secured to the wheel and pivotally connected to the other leaf, an electric motor for operating the wheel, and means for closing the circuit through the motor including platform operated switches arranged on opposite sides of the door.

In testimony whereof I affix my signature in the presence of two witnesses:

GEORGE DAVIS HALL.
